(57) **CLAIM**

The ornamental design for a fan with stand, as shown and described.

DESCRIPTION

FIG. 1 is a PERSPECTIVE view of a fan with stand of the present invention;

FIG. 2 is a PERSPECTIVE view thereof, but shown in an alternate position;

FIG. 3 is a TOP view of FIG. 1;

FIG. 4 is a BOTTOM view thereof;

FIG. 5 is a LEFT SIDE view thereof;

FIG. 6 is a RIGHT SIDE view thereof;

FIG. 7 is a FRONT view thereof; and,

FIG. 8 is a BACK view thereof.

The broken lines illustrate portions of the fan with stand and form no part of the claimed design.
